UNITED STATES PATENT OFFICE

LOUIS KASAN, OF NEW YORK, N. Y.

AWNING

Application filed November 7, 1927. Serial No. 231,555.

This invention relates to awnings, and its principal object is to provide an improved awning having simplified, efficient, and improved means for rapidly and conveniently assembling the awning, for rapidly and conveniently installing the awning, and for rapidly and conveniently removing the awning for storage.

Another object is to provide an awning the top cloth of which is attachable to and detachable from the awning frame, and the side-cloths of which are attachable to and detachable from said frame and to and from the top cloth.

Another object is to provide an awning the frame-lifting rope of which carries means for attaching it to and detaching it from the frame, and the rope-guiding means of which permits removal therefrom of the rope laterally relatively to the top cloth.

Another object is to provide an awning, the side-cloths of which are equipped with efficient and improved means for the lateral ventilation of the awning.

Other objects and advantages will herein-after appear.

In the accompanying drawings,—

Fig. 1 shows a perspective view of the awning.

Fig. 2 is a cross-sectional side elevation of a portion of the awning.

Fig. 3 shows a rear view of a portion of the awning-top cloth.

Figs. 4 to 9 show details of the awning.

The awning 1 proper comprises a top-cloth 2, side-flap cloths 3, a hinged lifting frame 4, and a lifting rope 5, the upper parts of the awning being shown separately in Figs. 8, 9, for clearness of illustration. The upper edge of the cloth 2 is secured to the window 6 in any suitable manner, and the lower end of this cloth is held to the frame 4 by means of passing it around the frame in the manner shown and securing its edge 7 to the underside of the cloth. The cloth-edge 7 is scalloped as shown in Fig. 3 and provided with a series of points 8, to each of which is secured a button-member 9 adapted to lock to and unlock from a cooperating spring-socket 10 secured to the

cloth 2, whereby the cloth is thus rendered attachable to and detachable from the frame 4. As here illustrated, the buttons 9 and sockets 10 coact in the manner of the well known glove fasteners. The side-flap cloths 3 are joined to the side-bars of the frame 4 in a similar manner, as shown in Figs. 1, 2; i. e., their lower edges 11 are similarly scalloped, providing points 8 and carrying buttons 9 which interlock with sockets 10 secured to the side-cloths. The sloping end 12 of each side-cloth 3 is pronouncedly scalloped, forming a series of pronounced points 13 which are secured to the adjoining edge of the top-cloth 2, whereby a series of openings 14 are formed, bounded by the edge 15 of the side-cloth 3 and the edge 16 of the top cloth 2, which openings thus provide efficient lateral ventilation to the interior of the awning and the interior of the room. A front apron 17 is preferably sewed to the top cloth 2 and side-aprons 18 are similarly sewed to the side-cloths 3, which aprons are joined to each other at their points 19 and provide corner openings 20 that aid further in the ventilation of the awning. The points 13 of the side-cloth 3 may be joined to the edge 16 of top-cloth 2 in the manner shown in Fig. 6, wherein a wire clip 21 passes through the two cloths and secures them to each other. Or, each of the points 13 may be provided with a spring gripping-device 22, Fig. 4, wherewith the point may be attached to or detached from the edge 16 of the top-cloth. The device 22 comprises a right-angularly bent plate 23 and a spring plate 24, which plates are jointly riveted to the point 13 at 25, and when in attached state the spring plate 24 presses the cloth-end 16 forcibly against the fixed plate 23 and thereby holds the two cloths 2, 3 to each other. Upon releasing the spring-plate 23, by pulling of the strap 26 thereof, the cloth points 13 and the cloth 3 are quickly disassembled from the top cloth. To the end of the lifting rope 5 is secured a fitting 27, which comprises a spring-plate that may be sprung apart so as to permit it passing around the frame-bar 4, as shown in Fig. 2, in which manner the rope 5 may be readily attached to and detached from the frame. The rope 100

5 passes through guide-rings 28 secured to loops 29 sewed to the top-cloth 2, which rings consist of spring-wire loops that may be spread apart to permit the rope to pass laterally into and out therefrom, and the advantage of these rings is that the top cloth may be completely removed without necessitating disassembly of the frame 4 and its lifting ropes 5. It will be noted that the scalloping 10 of the cloth-ends 7, 11 eliminates the sag which might otherwise occur in the cloth in the region between the securing buttons 9. To each side-rod 30 of frame 4 is secured a fitting 31 in which is telescopically joined the end of 15 the front bar 32 of said frame, as shown in Fig. 5, whereby this frame may be thus adjusted laterally to the precise width of the window, and the frame may be then fixed in such adjusted condition by means of tightening 20 of the set-screws 33. It will be evident that by the various means hereinabove illustrated and described the above awning parts may be quickly, conveniently, and without the use of tools, assembled, installed, or removed 25 for storage.

In the modification shown in Fig. 7 the fitting 27 is secured directly, by means of rivets 34, to the top cloth 2, and the apron 17^a forms an integral part of the top cloth, in which manner this fitting serves as a lifting means for the frame 4 and simultaneously, whether with or without having the rope 5 attached thereto, also as an attaching means for the top cloth 2 with the frame.

In Figs. 8, 9 is shown the preferred mode of attaching or suspending the upper end 35 of the top cloth 2 to the window 6. The upper edge of the cloth is hemmed around a piece of roping 36, thus forming the thickened end 40 35, which is slipped lengthwise into a sheet-metal channelled frame 37 that engages it firmly. Said frame is in turn slipped lengthwise into two or more fittings 38, which thus firmly hold it and are provided with ears 39 that are hung upon hooks 40 screwed into the window-frame 6. A thumb-screw 41 threads through the fitting 38 and bears against the channelled frame 37 and therethrough on the cloth-end 35, thereby insuring against lateral dislocation of all these parts. The fitting 38 is provided with a hook 42 upon which is suspended an operating pulley 43 for the guidance and manipulation of the lifting rope 5.

Variations may be resorted to within the 55 scope of the invention, and portions of the improvements may be used without others.

Having thus described my invention, I claim:—

60 1. An awning having the combination of a top cloth, a side-flap cloth, said cloths being secured to each other at a plurality of places, said side-flap cloth being so configurated that it provides a ventilating opening between 65 each adjoining pair of said places, and said

ventilating opening being bounded by the edges of said two cloths.

2. An awning having the combination of a top cloth, a side-flap cloth, said latter cloth being scalloped so as to form a plurality of 70 projections, and said projections being joined to said top cloth so as to form a series of ventilating openings in said side-flap cloth, each of which is bounded by both of the cloths. 75

3. An awning having the combination of a top cloth, a side-flap cloth, said latter cloth being scalloped so as to form a plurality of 80 projections, said projections being joined to said top cloth so as to form a series of ventilating openings in said side-flap cloth, each of which is bounded by both of the cloths, and said projections being attachable to and detachable from said top cloth for installation and removal of the awning. 85

4. An awning having the combination of a top cloth, a side-flap cloth, an apron cloth for said top, an apron cloth for said side-flap, and said apron cloths being joined to each other so as to leave an opening between them 90 bounded by their edges.

5. An awning having the combination of a top cloth, a side-flap cloth, and a plurality of fastening devices for attaching said cloths to and detaching them from each other. 95

6. An awning having the combination of a top cloth, a side-flap cloth, and a plurality of spring-actuated devices for attaching said cloths to and detaching them from each other.

7. An awning having the combination of a frame, a rope for lifting said frame, a suspension device secured to said rope, and said device sustaining said frame. 100

8. An awning having the combination of a frame, a rope for lifting said frame, a suspension device secured to said rope, and said device being attachable to and detachable from said frame. 105

9. An awning having the combination of a frame, a rope for lifting said frame, a suspension device secured to said rope, and said device being springy to attach to and detach from said frame. 110

10. An awning having the combination of a frame, a rope for lifting said frame, a top cloth, a guiding device for said rope secured to said cloth, and said device having means for slipping the rope thereinto and out therefrom laterally. 115

11. An awning having the combination of a cloth, a frame, a rope for lifting said frame, a suspension device secured to said rope, said device sustaining said frame, and said cloth being secured to said device. 120

12. An awning having the combination of a cloth, a frame, a suspension device for sustaining said frame, and said cloth being secured to said device. 125

13. An awning having the combination of a cloth, a frame, a suspension device attach- 130

able to and detachable from said device, and said cloth being secured to said device.

14. An awning having the combination of a cloth, a frame, a suspension device for sustaining said frame, said cloth being secured to said frame, and said device being springy to attach to and detach from said frame.

15. An awning having the combination of a top cloth, a pivoted operating frame for raising and lowering said cloth, the lower end of said cloth being folded around said frame and toward the underside of the cloth and being adapted to sustain the frame by means of the folded portion, said underside of the cloth having secured thereto an attaching and detaching device, and said end of the cloth having secured thereto a cooperating device for attaching it to and detaching it from said other device.

20 16. An awning having the combination of a top cloth, a pivoted operating frame for raising and lowering said cloth, the lower end of said cloth being folded around said frame and toward the underside of the cloth and being adapted to sustain the frame by means of the folded portion, said underside of the cloth having secured thereto a plurality of attaching and detaching devices, said end of the cloth being scalloped so as to form a plurality of points corresponding to said devices, and said end of the cloth having secured at each of said points a cooperating device for attaching it to and detaching it from said other devices.

35 17. An awning having the combination of a top cloth, a pivoted operating frame for raising and lowering said cloth, the lower end of said cloth being folded around said frame and toward the underside of the cloth and being adapted to sustain the frame by means of the folded portion, said underside of the cloth having secured thereto an attaching and detaching device, said end of the cloth having secured thereto a cooperating device for attaching it to and detaching it from said other device, a side-flap cloth having its lower end folded around said frame and toward the inner side thereof, said inner side having secured thereto an attaching and detaching device, and the end of said side-flap cloth having secured thereto a cooperating device for attaching it to and detaching it from said inner side of the cloth.

55 18. An awning having the combination of a top cloth, a pivoted operating frame for raising and lowering said cloth, the lower end of said cloth being folded around said frame and toward the underside of the cloth and being adapted to sustain the frame by means of the folded portion, said underside of the cloth having secured thereto a plurality of attaching and detaching devices, said end of the cloth being scalloped so as to form a plurality of points corresponding to said devices, said end of the cloth having secured

at each of said points a cooperating device for attaching it to and detaching it from said other devices, a side-flap cloth having its lower end folded around said frame and toward the inner side thereof, said inner side having secured thereto a plurality of attaching and detaching devices, the end of said side-flap cloth being scalloped so as to form a plurality of points corresponding to the devices upon said inner side, and the end of said side-flap cloth having secured at each of its points a cooperating device for attaching it to and detaching it from said inner side of the cloth.

Signed at the city of New York, in the county of New York, and State of New York, this 31st day of October, A. D. 1927.

CERTIFICATE OF CORRECTION.

Patent No. 1,750,271.

Granted March 11, 1930, to

LOUIS KASAN.

It is hereby certified that error appears in the printed specification of the above numbered patent requiring correction as follows: Page 3, line 1, claim 13, for the word "device" read "frame"; same page, line 6, claim 14, for the word "frame" read "device"; and that the said Letters Patent should be read with these corrections therein that the same may conform to the record of the case in the Patent Office.

Signed and sealed this 22nd day of April, A. D. 1930.

(Seal)

**M. J. Moore,
Acting Commissioner of Patents.**
